H. KOCOUREK,
ANIMAL SHEARS,
APPLICATION FILED OCT. 11, 1920.

1,404,301.

Patented Jan. 24, 1922.

UNITED STATES PATENT OFFICE.

HENRY KOCOUREK, OF CHICAGO, ILLINOIS, ASSIGNOR TO CHICAGO FLEXIBLE SHAFT COMPANY, OF CHICAGO, ILLINOIS, A CORPORATION OF ILLINOIS.

ANIMAL SHEARS.

1,404,301.

Specification of Letters Patent. Patented Jan. 24, 1922.

Application filed October 11, 1920. Serial No. 416,144.

To all whom it may concern:

Be it known that I, HENRY KOCOUREK, a citizen of the United States, residing in the city of Chicago, in the county of Cook and the State of Illinois, have invented certain new and useful Improvements in Animal Shears, of which the following is a specification, reference being had to the accompanying drawings, forming a part thereof.

10 The purpose of this invention is to provide an improved construction of animal shears of the general class which are hand-directed and adapted to be power-driven, and of the type which are especially adapted 15 for sheep-shearing. It consists of the features of construction shown and described, as indicated in the claims:

In the drawings:

Figure 1 is a top plan view of a sheep 20 shear embodying this invention with the cover plate removed.

Figure 2 is a section at the line, 2—2, on Figure 1.

Figure 3 is an inverted detail plan view 25 of certain operating parts for actuating the reciprocating cutter.

Figure 4 is a front elevation of the part shown in Figure 3.

Figure 5 is a section at the line, 5—5, on 30 Figure 3.

Figure 6 and Figure 7 are views similar to Figures 4 and 3, respectively, showing a modified construction.

Figure 8 is a top plan view of the construction shown in Figures 6 and 7.

Figure 9 is a view of a second modification.

Figure 10 is a section at the line, 10—10, on Figure 7.

Figure 11 is a section at the line, 11—11, on Figure 10.

The structure shown in the drawings is in general, substantially of a familiar type of sheep shear which comprises a housing 45 or base, 1, of which the portion, 1^b, may be called the handle piece and which has the bearing for the driving shaft, 2, said shaft having at its forward end the crank plate, 3, whose crank wrist or stud, 3^a, carries a ball member, 3^b, for engaging the vertical slot, 4^a, in the rear end of the actuating lever, 4, which at its forward end is expanded transversely to form a head, 4^b, being intermediately fulcrumed upon a spherical-headed pivot eye mounted in the lower side

of the casing, 1. A dolly pin, 8, seated at its lower end at 4^c, in the upper side of the lever, 4, extends up into the turret, 9, to reach the pressure-adjusting screw, 10, of familiar construction for applying the pressure for holding the vibrating cutter, 6, in proper contact with a fixed comb-cutter, 7, which is secured at the forward end upon the under side of the casing, 1, all in a familiar manner. This shear is of the type which has a plurality of pressers, 11, having fingers, 11^a, for bearing upon the respective blades, 6^a, of the vibrating cutter, 6, said pressers having each a spindle or stem, 11^b, by which the presser is pivotally mounted 65 in the head of the actuating lever 4, with freedom for rocking about its stem, which is cylindrical, to apply the pressure transmitted through the dolly pin to the actuating lever and thence to the presser, equally 70 upon the finger or fingers of the presser which bear upon the respective blades, 6^a, of the vibrating cutter.

One feature of this invention relates to the means for securing the pressers at their 80 pivotal mounting in the head of the actuating lever. Heretofore this has been done by means of a key pin set through the bearing of the stem of the presser in the lever head, and engaging an annular groove 85 encompassing the cylindrical stem of the presser. Besides the inconvenience involved in removing the key pin when it is necessary to substitute a new presser for a worn one, and the liability of the pin itself to escape 90 in use when it is so made that it can readily be removed, there has been found a further serious objection to this mode of mounting the presser, arising from the fact that this presser, which is hard tempered, and therefore liable to breakage, when one of its fingers is broken is liable to turn at its bearing in the head of the actuating lever, swinging the unbroken finger into engagement 95 with the fingers of the fixed comb cutter 100 while the tool is operating at the high rate of speed at which it is operated, which frequently amounts to three thousand oscillations per minute, with the result that the comb has its fingers broken, and the entire 105 tool is exposed to severe strain in other parts, all consequent upon the breaking of the finger of the presser. This difficulty is avoided and the injury which results from the defect mentioned is prevented by the 110

construction shown in the drawings which consists in providing the spindle or stem of the presser with a flat key seat at one side as shown at 11^x, and providing a flat spring 5 key, 12, which is conveniently made as seen in the inverted plan view of Figure 3, in T-form, having its stem secured by screw 12^b, the two ends of the cross of the T serving as keys for the two spindles of the two 10 pressers whose bearings are apertured to admit said cross arm into the flat key seat of the spindles, above mentioned. The ends of the spindles are provided with a slight bevel at one side, as seen at 11^d, to facilitate 15 their engagement under the spring key when the spindles are pushed in from the open end of the bearing. By turning the presser on its axis in its bearing 90 degrees or more around from the position of engagement of 20 the flat key seat by the spring key, the spindle becomes disengaged from the key and may be withdrawn. It will be understood, moreover, that the flat key seat terminates in abrupt shoulders as seen at 12^y, 25 so that the key holds the presser securely in the bearing against longitudinal escape or displacement; and it will be understood that the flat seat engaged by the flat key prevents the presser from turning in the bearing as 30 it might do upon the breaking of one of the fingers, if it were not for this construction preventing it.

Another feature which characterizes the structure shown in the drawings, consists 35 in the means of securing in the head of the actuating lever the pin, 15, which engage holes, 6^x, in the vibrating cutter for driving it. Customarily, heretofore, pins for this purpose have been riveted into the lever 40 head, causing serious difficulty when it was necessary to remove the pins on account of the wear to which they are exposed, which often has to be done in the field where tools and facilities are inadequate, resulting in 45 breaking out the holes in which the pins are riveted, and thereby ruining the lever, necessitating its replacement. In the construction shown in the drawings, the holes in the head of the lever in which the pins are seated 50 are slightly tapered, and the upper ends of the pins are correspondingly tapered so that they may be driven tight into the lever, being prevented from escaping while in service, if they should become loose, by the 55 fact that the holes in the vibrating plate with which they are engaged are at all times closed at the lower end by the fixed comb cutter over which the vibrating plate travels.

A special feature of the present invention 60 is designed to permit employing the construction which involves the pivoted pressers having fingers engaging respective blades of the vibrating cutter, in tools of which the breadth of the tool the length of its cutting 65 front, is only sufficient for three blades of

the vibrating cutter or any construction in which the vibrating cutter has an odd number of blades. In such case, either two adjacent pressers must have their proximate fingers both bearing upon the same blade, or they 70 must in some manner be engaged with each other so that the same blade will serve to take the pressure from both which is necessary to counterbalance pressure of the remote fingers of the two adjacent pressers. 75 There are shown in the drawings two methods of effecting this result. In Figures 4 and 5 the method consists in providing the two adjacent pressers with inter-engaging gear segments, 17, 17, by which the rocking 80 of either presser is communicated in the opposite direction to the other, so that the pressure of either is transmitted to the other in and by the rocking movement. By this means, either of the two pressers which has a 85 finger for pressing upon the blade of the cutter which is intermediate the two blades by which the remote fingers of the two pressers are lodged, serves to transmit the resistance of that blade to the other presser for 90 offsetting and balancing the resistance of the remote blade upon which the sole finger of the other presser is lodged. And in the Figures 4 and 5, one of the pressers is shown 95 having only a single finger while the other 95 presser has two fingers one of which bears alone upon the intermediate blade of the cutter.

Another and substantially equivalent method of accomplishing the result, consists 100 in making the proximate fingers of the two pressers with inter-engagement, practically equivalent to gear engagement, by which they transmit pressure to each other, while at the same time both may be pressing upon 105 the intermediate blade. This construction is seen in Figures 6 and 7, the interengagement of the proximate fingers of the two pressers substantially equivalent to a segment gear, being seen at 18. A third method 110 is shown in Figures 8, 9 and 10, which consists in constructing the proximate fingers 115 of the two pressers so that one extends behind the other, both being lodged upon and transmitting pressure to and experiencing resistance from the same intermediate blade of the cutter. The proximate fingers of this construction are shown at 19 and 20, in Figures 9 and 10, mentioned.

I claim:—

1. In an animal shear having a fixed comb cutter, a vibrating cutter and an actuating lever for the latter, the vibrating cutter having an odd number of blades; pressers having fingers for bearing on the blades respectively, said pressers being pivotally mounted on the cutter-actuating lever with their pivot axes substantially radial with respect to the lever fulcrum; two adjacent pressers having their remote fingers bearing on non- 125

- adjacent blades, and at least one finger between said remote fingers, bearing on a blade intermediate said non-adjacent blade; and means by which said adjacent pressers 5 are engaged with each other for transmitting pressure from one to the other in rocking about their respective pivot axes on the actuating lever.
2. In the construction defined in claim 1, 10 foregoing, the means for transmitting pressure in the rocking of the pressers, being equal gear elements on the two pressers.
3. In the construction defined in claim 1, 15 foregoing, the two adjacent pressers having each two presser fingers, their proximate fingers being positioned for pressure on the same blade, and being directly engaged with each other for transmitting pressure in their rocking movement.
4. In an animal shear having a fixed comb cutter, a vibrating cutter and an actuating lever for the latter, a vibrating cutter having a plurality of cutting blades; a plurality of pressers having fingers for pressing upon 25 the blades respectively, said pressers having round stems by which they are pivotally mounted on the lever; a flat spring mounted for pressing laterally on said stems, the stems having flat key seats for lodgment of 30 said flat spring keys, abruptly shouldered for stopping the stem longitudinally when the key is lodged in the seat.
5. In the construction defined in claim 4,
- foregoing, the ends of the stems having a bevel for entering under the spring key in 35 inserting the stems in their pivot bearings in the lever.
6. In an animal shear, comprising a fixed comb cutter, a vibrating cutter and an actuating lever for the latter, the vibrating cutter having holes for engagement of driving pins, and driving pins carried by the actuating lever, said pins having slightly tapered stems, and the levers having correspondingly tapered holes extending through it 40 into which the tapered pins are driven tight for holding them in the lever, and are accessible at the upper end for loosening from the lever for removal and replacement.
7. In an animal shear, having a fixed 45 comb cutter, a vibrating cutter and an actuating lever for the latter, the vibrating cutter having an odd number of blades, pressers having fingers for bearing on the blades, respectively, said pressers being pivotally 50 mounted on the cutter-actuating lever with their pivot axes extending longitudinally with respect to the lever; two adjacent pressers having their remote fingers bearing upon non-adjacent blades of the vibrating 55 cutter, and their proximate fingers upon the same intermediate blade.

In testimony whereof, I have hereunto set my hand at Chicago, Illinois, this 8 day of October, 1920.

HENRY KOCOUREK.
